CLOTHES CHEST

Orville Mannen, Fort Wayne, Ind.

Application April 29, 1947, Serial No. 138,669

Term of patent 3½ years

Cl. D33—19)

To all whom it may concern:

Be it known that I, Orville Mannen, a citizen of the United States, residing at Fort Wayne, county of Allen, and State of Indiana, have invented a new, original, and ornamental Design for a Clothes Chest, of which the following is a specification, reference being had to the accompanying drawing, forming part thereof, and wherein:

Figure 1 is a perspective view of a clothes chest embodying my new design, with the front door of the chest in open position and the mirror-top in raised position.

Figure 2 is a front elevational view of the chest with the front door in closed position and the mirror-top in lowered position, and

Figure 3 is a top plan view of the clothes chest.

The characteristic feature of the present design resides in the shallow recessed-appearing top panel having marginal inwardly bevelled surface portions rimming the recess in association with the mirrored lid having outwardly bevelled sur-

face portions, all in relation to the remaining portions of the clothes chest, as shown.

I claim:

The ornamental design for a clothes chest, as shown and described.

ORVILLE MANNEN.
